CLAIM

The ornamental design for a hand dryer, substantially as shown and described.

DESCRIPTION

FIG. 1 is a front, raised perspective view of a hand dryer according to a first embodiment of the invention; FIG. 2 is a front view of the hand dryer of FIG. 1; FIG. 3 is a rear view of the hand dryer of FIG. 1; FIG. 4 is a right side view of the hand dryer of FIG. 1; FIG. 5 is a left side view of the hand dryer of FIG. 1; FIG. 6 is a top view of the hand dryer of FIG. 1; FIG. 7 is a bottom view of the hand dryer of FIG. 1; FIG. 8 is a front, raised perspective view of a hand dryer according to a second embodiment of the invention; FIG. 9 is a front view of the hand dryer of FIG. 8; FIG. 10 is a rear view of the hand dryer of FIG. 8; FIG. 11 is a right side view of the hand dryer of FIG. 8; FIG. 12 is a left side view of the hand dryer of FIG. 8; FIG. 13 is a top view of the hand dryer of FIG. 8; and, FIG. 14 is a bottom view of the hand dryer of FIG. 8. The broken lines depicting the center portion of the horizontal edges of the hand dryer are for illustrative purposes and form no part of the claimed design.

1 Claim, 14 Drawing Sheets
